UNITED STATES PATENT OFFICE.

EDGAR WILSON CLARK, OF GREELEY, COLORADO.

ARTICLE HOLDER.

Application filed November 24, 1924. Serial No. 751,787.

This invention relates to article holders, and more particularly to a holder for newspapers, periodicals and the like and adapted to be arranged upon a lawn in front of a house to receive the paper or periodical as it is brought by the newsboy or postman.

An important object of the invention is to provide a device of this character so constructed that it may be very cheaply and readily produced and will be durable and efficient in service.

A further object of the invention is to provide a device of this character so constructed that when a paper or periodical is placed therein and a wind is blowing it will swing to present the end of the paper or periodical to the wind so that the same will not be unduly frayed or injured by the play of the wind thereagainst.

These and other objects I attain by the construction shown in the accompanying drawing, wherein for the purpose of illustration is shown a preferred embodiment of my invention, and wherein:—

Figure 1 is a side elevation of an article holder constructed in accordance with my invention;

Figure 2 is a view at right angles to that shown in Figure 1;

Figure 3 is a section on the line 3—3 of Figure 1.

Referring to the drawing, the device consists of a shank 10 adapted to be forced into the ground and having at its upper end a coil 11 lying to one side of the shank, this coil being formed with a plurality of turns of considerable size, preferably about one foot in diameter. At their lower ends the turns of the coil are bound to one another by a clip 12 held in position by the extremity of the piece of material from which the coil is formed, this extremity being bent to form a loop 13, the end portion of which engages against the side face of the coil, as indicated at 14, to prevent slipping of the clip. By this construction a plurality of wedge-shaped slots are formed, and if the

material employed in the formation of the coil be resilient the insertion of a paper or periodical in the coil will tend to wedge the coil open so that it exercises a clamping effect to hold the paper in position. The coil being off-set to one side of the shank 10, if a paper is inserted in the coils will operate as a weather-vane, placing the strain in proportion to the force of the wind, tending to rotate the shank 10 until the coil lies in such position that a plane transverse to its axis is directed into the wind, thus directing the end of the article into the wind and preventing tearing or distortion thereof which would tend to fray the article at its point of engagement with the coils.

In the construction of the device, the shank 10 and coil 11 are preferably formed from a single length of wire, one end of which is left straight to provide the shank and the opposite end of which is coiled to provide the coil 11 and the retaining end portion or loop 13.

It will be obvious from the foregoing that a paper holder constructed in accordance with my invention may be very cheaply and readily produced and is of such construction that it will be relatively long-lived. Since obviously some modification of the structure is possible, I do not limit myself to such specific structure except as hereinafter claimed.

I claim:—

A holder for newspapers, periodicals or the like comprising a round shank adapted to be inserted in the ground and provided at its upper end with a coil having a plurality of turns and disposed to one side of the shank and tangential thereto, and a clip constricting the coil at the bottom thereof, an end portion of the coil being bent to engage the coil in spaced relation to the end thereof to thereby provide a loop through which the clip is directed and from which the clip may not escape.

In testimony whereof I hereunto affix my signature.

EDGAR WILSON CLARK.
